(57) **CLAIM**

The ornamental design for a gasifier for heating as shown and described.

DESCRIPTION

1. Gasifier for heating

1.1 is a front elevational view of a gasifier for heating;

1.2 is a rear elevational view thereof;

1.3 is a left side view thereof;

1.4 is a right side view thereof;

1.5 is a top plan view thereof;

1.6 is a bottom plan view thereof;

1.7 is a front perspective view thereof.

The broken lines shown in the drawings are included for the purpose of illustrating portions of the gasifier for heating that form no part of the claimed design.
